Specification for Design.

Patented Mar. 27, 1917.

Application filed February 9, 1917. Serial No. 147,710. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for an Arm for Chandeliers and Brackets, of which the following is a specification, reference being had to the accompanying drawing, forming a part thereof, wherein—

Figure 1 is a front elevation, and
Fig. 2 is a side elevation showing an arm
for chandeliers and brackets embodying my
improved design.

I claim as my invention:
The ornamental design for an arm for
chandeliers and brackets, as shown.

CHARLES ERNEST JONES.
